UNITED STATES PATENT OFFICE.

JAMES W. IVORY, OF PHILADELPHIA, PENNSYLVANIA.

DEVICE FOR SHARPENING DENTAL STICKS, &c.

1,121,252.

Specification of Letters Patent.

Patented Dec. 15, 1914.

Application filed June 10, 1913. Serial No. 772,771.

To all whom it may concern:

Be it known that I, JAMES W. IVORY, a subject of the King of Great Britain, residing in the city and county of Philadelphia, State of Pennsylvania, have invented a new and useful Device for Sharpening Dental Sticks, &c., of which the following is a specification.

My invention consists of a device adapted to sharpen or point a dental stick, a lead pencil, or other object in a convenient and easy manner, the same embodying a stock into which the object may be inserted, a blade or cutter thereon, and a pressure device adapted to properly retain said object resiliently against said blade or cutter, and to assist in guiding said object in its motion into and out of said stock.

It consists also of means for adjusting the angle of the blade or cutter, and other details as will be hereinafter described.

The invention is satisfactorily illustrated in the accompanying drawing, but the important instrumentalities thereof may be varied, and so it is to be understood that the invention is not limited to the specific arrangement and organization shown and described.

Figure 1 represents a perspective view of a device for sharpening or pointing a dental stick, lead pencil, etc., embodying my invention. Fig. 2 represents a partial longitudinal section and partial side elevation thereof. Figs. 3, 4, and 5 represent partial longitudinal sections and partial side elevations of other embodiments thereof.

Similar numerals of reference indicate corresponding parts in the figures.

Referring to the drawings:—1 designates a tubular stock to one end of which is secured the handle 2 for convenience of operation of the device. In the wall of said stock in the end portion opposite to said handle is the throat 3, the upper wall of which is sharpened forming the blade or cutter 4 which projects in the direction toward said throat.

To the stock at the rear end of said throat is secured the plate 5 which forms a wear plate and provides a gage for setting the pencil, stick, or other object to be sharpened properly in the stock 1 preparatory to the cutting operation therein.

Below the blade or cutter 4 is the pressure bar 6, which is a continuation of or

connected with the resilient elbow 7, whose lower limb is secured to the underside of the stock, as at 8. The upper face of said bar is sufficiently long and wide to allow the pencil or stick to rest therein during its sliding motions and to be guided while being subjected to the cutting or sharpening action.

The inlet end of the stock 1 is of the form of a conical head 9 which primarily receives the portion of the pencil or stick to be sharpened and the underside of said head is cut away so as to receive the adjacent portion of the elbow 7 and allow it to play therein and yield to pressure.

It will be seen that when the stick or pencil or other object is inserted in the head 9 the portion within the same rides upon the bar 6 and depresses the same so as to exert an upward pressure on said portion and hold it resiliently against the blade 4. The end of the object then reaches the plate 5 and abuts therewith as a stop and gage, see Fig. 2. The object is then drawn out, in the present case to the right, and somewhat lowered, when it is forcibly presented to the blade and at an angle thereto, said blade then removing a corresponding part of the wood of the object. Then the object is turned and reinserted into the head, when it is drawn out again, and so another portion of the wood is cut. Then the work continues, until the object is sharpened or pointed to the required extent.

In Figs. 3, 4, and 5, the stock has on its under side below the upper limb of the elbow 7, the forwardly projecting tongue 10 which serves as an abutment to limit the descent of said limb when depressed by the pencil or stick superimposed thereon.

In Fig. 4, the blade or cutter 4 is made separate from the head 9 and secured thereto by the screw 11, while in Fig. 5, the blade or cutter likewise is made separate from the head 9, and is pivotally connected with the latter as at 12 and provided with a set screw 13 whose point rests upon said head whereby by the proper rotation of said screw the angle of the cutter or blade may be varied according to requirements.

It will be seen also that the portion of the stock between the same and the head 9 comprises necks 14 which carry the head 9, and the latter is flaring or conical, the widest end being in front whereby the stick

or object to be sharpened or cut may be easily inserted thereto and be presented to the blade at the proper angle. Again, the pressure bar terminates at or beyond the cutting edge of said blade in said throat so as to effectively hold the pencil or stick to said edge.

10 The side of the stock is divided by means of a longitudinally-extending slot 15 thus serving to add greater resiliency to the elbow 7 and consequently to the pressure bar 6 and the tongue 10.

15 The cutting edge 4 of the head 9 is at the forward end of the throat 3 whereby it presents itself conveniently to the pencil or stick, and is also convenient of access for sharpening purposes.

20 It is apparent that as the portion 2 of the stock is grasped as a handle, the device may be firmly held and controlled, while the stick, pencil, or other object is being manipulated in the head 9, during the cutting, sharpening, or pointing of the same.

25 Having thus described my invention what I claim as new and desire to secure by Letters Patent, is:—

30 1. In a sharpening or pointing device of the character stated, a longitudinally slotted stock, a cutting edge thereon, and a pressure bar adjacent to said edge and comprising a forwardly extending portion, a return bend, and a rearwardly extending portion above said forwardly extending portion and below the throat of the stock.

35 2. In a sharpening or pointing device of the character stated, a longitudinally slotted stock, a cutting edge thereon, and a resilient pressure bar extending forwardly from beneath the throat of said stock to beyond the cutting edge and then back to be depressed by the article to be sharpened, the free edge

of said pressure bar normally extending angularly within the said throat.

3. In a sharpening or pointing device of the character stated, a tubular stock, a semi-tubular head, a cutting edge on the inner end of said head, said stock having a throat into which said cutting edge projects, a resilient pressure bar supported on the under side of the stock and extending angularly 45 within the throat for supporting the article to be sharpened with the latter in alinement with said stock, and a forwardly projecting member serving as an abutment to limit the depressible movement of said pressure bar. 50

4. In a sharpening or pointing device of the character stated, a tubular stock, a cutting edge thereon, a pressure bar adjacent to the latter, a resilient elbow of which said pressure bar forms a continuation, said stock being longitudinally slotted and having a throat and the free end of the pressure bar extending angularly into said throat and beneath said cutting edge whereby said free end will limit the depression of the article to be sharpened. 65

5. In a sharpening or pointing device of the character stated, a stock having a semi-tubular head and a cutting edge thereon and a throat into which said edge projects angularly, resilient necks intermediate of said head and stock and carrying said head and an elbow terminating in a pressure bar said elbow being carried by said stock and said pressure bar projecting into the throat beneath the cutting edge at an angle to said angular cutting edge. 70 75
